US00D868033S

(12) **United States Design Patent** (10) Patent No.: **US D868,033 S**
 (45) Date of Patent: **** Nov. 26, 2019**

(54) **LOUDSPEAKER**(71) Applicant: **Shenzhen Weiking Technology Co., Ltd**, Shenzhen, Guangdong (CN)(72) Inventor: **Fuguang Luo**, Guangdong (CN)(73) Assignee: **Shenzhen Weiking Technology Co., Ltd**, Shenzhen (CN)(***) Term: **15 Years**(21) Appl. No.: **29/638,782**(22) Filed: **Feb. 28, 2018**(51) LOC (12) Cl. **14-01**

(52) U.S. Cl.

USPC ..... **D14/216**(58) **Field of Classification Search**

CLAIM

The ornamental design for a loudspeaker, as shown and described.

DESCRIPTION

FIG. 1 is a front elevational view of a loudspeaker showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front perspective view thereof;

FIG. 8 is a rear perspective view thereof; and,

FIG. 9 is a left side perspective view thereof.
